UNITED STATES PATENT OFFICE.

FELIX GUETTHOFF, OF THREE RIVERS, MICHIGAN.

SWIMMING DEVICE OR LIFE-PRESERVER.

1,217,756.

Specification of Letters Patent. Patented Feb. 27, 1917.

Application filed October 25, 1916. Serial No. 127,652.

To all whom it may concern:

Be it known that I, FELIX GUETTHOFF, a citizen of the United States, residing at Three Rivers, in the county of St. Joseph and State of Michigan, have invented new and useful Improvements in Swimming Devices or Life-Preservers, of which the following is a specification.

This invention relates to a swimming device or life preserver, designed to be worn upon the person of the wearer and beneath a bathing suit or other swimming garment or clothing for the purpose of buoying or supporting the wearer in a body of water, the primary object of the invention being to provide a device which will assist a beginner and give him confidence in the art of swimming, as well as assisting skilled swimmers in swimming in rough water, and further to serve, as a life preserver if desired.

A further object of the invention is to provide a swimming device or life preserver which consists of a body of material either impervious to water or which is rendered so by immersion in the water, and which is provided with a novel construction and arrangement of air chambers and passages leading thereto, whereby the device may be inflated so as to have a maximum degree of buoying action.

A still further object of the invention is to provide a swimming device or life preserver which is simple of construction, reliable and efficient in action, comparatively inexpensive of production, and in which foldable plaits are provided which normally lie in folded condition but communicate with the air chambers and are adapted to be expanded or opened upon the expansion of the chambers to increase the area thereof.

With these and other objects in view, the invention consists of the features of construction, combination and arrangement of parts hereinafter fully described and claimed, reference being had to the accompanying drawing, in which:—

Figure 1 is a view showing the application of the invention.

Fig. 2 is a plan view of the device looking toward the outer surface thereof.

Fig. 3 is a horizontal transverse section.

Fig. 4 is a vertical longitudinal section on line 4—4 of Fig. 2 showing the device in normal condition.

Fig. 5 is a similar view showing the device expanded.

In carrying my invention into practice I provide a swimming device or life preserver 1 which is adapted to be applied to the breast of the wearer and is of suitable shape 60 to fit the same and to extend downward from the neck to a point below the waist line. The device is provided at its sides with partly circular arm-hole recesses 3 to adapt the device to extend under the arm 65 pits, and above and below the respective arm-hole recesses the device is provided with tabs or projections 4 and 5. These tabs are provided with buckles, or other suitable fastening means 6 for connection 70 with straps 6' for securing the device about the chest and waist of the person of the wearer.

The device is made of inner and outer plies 7 and 8 of a suitable light strong and 75 durable material, which may be in the nature of water-proof material or a fabric or other material rendered proof against the escape of air upon immersion in the water. These plies of material are marginally united by a 80 line of stitching 9, and are also united by transverse lines of stitching 10 and vertical lines of stitching 11, whereby the space between the plies is sub-divided into a plurality of air chambers 12. As shown in the 85 present instance, these air chambers are arranged in two vertical rows, one on each side of the vertical center of the device, there being four chambers in each vertical row, or eight chambers in all, but any other suitable 90 number of chambers may be employed, provided the chambers are so arranged as to give a balance or proper degree of buoying action, when the chambers are inflated, throughout the area of the device. By the 95 construction described air supply or inflating passages 13 are formed centrally of the device and communicate through lateral outlets 14 with the respective chambers, said passages being in communication at their 100 upper ends with each other and with a suitable inflating valve 15 carried by a tab 16 projecting centrally from the upper marginal edge of the device. Air is forced into the chambers through this valve so as to fill 105 the chambers under the desired degree of pressure, whereby the device will be inflated for flotation in an obvious manner.

In order to increase the air containing capacity of the air chambers, portions of the 110 outer ply 8 and the lines of stitching are so arranged as to form longitudinal and trans-

verse plaits, 17 and 18 which communicate with the respective air chambers. When the device is in normal or uninflated condition these plaits lie snugly against the outer ply, 5 thus allowing the device to be folded and packed in close compass, but when the device is inflated the plaits are inflated also and form extended buoying surfaces, adding materially to the buoying capacity of the device. 10 In practice, the device is designed to snugly fit upon the breast and about the body of the wearer and is to be used beneath a bathing or swimming suit or beneath the clothes, the compact form allowing it to be 15 worn with great convenience in this connection. It will be apparent that when the device is so applied in inflated condition it will, through its buoyancy, support the wearer in a body of water, thus enabling 20 him to take swimming lessons with confidence, to float and to perform other evolutions in the water, as well as enabling an experienced swimmer to swim with greater confidence and ease in rough water. The 25 device may also be employed to perform the function of a life preserver, as will be readily understood.

I claim:—

1. A swimming device or life preserver comprising a body adapted to be secured to the person of the wearer, said body consisting of outer and inner plies united by longitudinal and transverse rows of stitching to form rows of air chambers on opposite sides thereof, and central longitudinal air passages communicating with the respective rows of chambers, the outer ply being provided with plaits or folds communicating with the air chambers and adapted to be inflated therefrom, and a valve communicating with said air passages.

2. A swimming device or life preserver comprising a body adapted to be secured to the person of the wearer and consisting of inner and outer plies united to form air chambers and passages communicating therewith, the outer ply being provided with plaits or folds normally lying parallel therewith and forming walls of the air chambers when inflated, and a valve communicating with said passages.

In testimony whereof I affix my signature.

FELIX GUETTHOFF.
